UNITED STATES PATENT OFFICE

2,555,352

AIR LAUNCHED RADIO STATION

Percival D. Lowell, Chevy Chase, and William Hakkarinen, Hyattsville, Md.

Application June 20, 1945, Serial No. 600,627

8 Claims. (Cl. 244—138)

(Granted under the act of March 3, 1883, as amended April 30, 1928; 370 O. G. 757)

1
Our invention relates to a radio station which may be dropped from an aircraft onto remote or hostile territory and there unattended will set itself into operation for transmission of signals, for example weather data such as pressure, temperature and humidity.

In accordance with one aspect of our invention, the station upon its release from a bomb-rack, or equivalent support, floats by parachute until contact with the earth initiates a series of events, including for example, release of the parachute, and elevation of an antenna, culminating in transmission, preferably periodical-ly, of weather data or other intelligence.

Further in accordance with our invention, the release of the parachute, the elevation of the antenna and erection of the station, when erecting legs are employed, are effected by explosive charges under control of a timing device, preferably the same device which controls the periods of transmission and silence of the radio trans-mitting equipment. Precautionary measures are taken to insure the explosive means are disabled until after the station is clear of the aircraft.

Further in accordance with our invention, to insure accuracy of the transmitted data despite possible deformation of relatively movable contacting parts due to landing impact, those parts are vibrated to ensure their proper relative position in response to change in pressure, tempera-ture or humidity, even though the deformation may greatly vary the contact pressure.

In accordance with other aspects of our in-vention, it is provided that change of electrical characteristics of circuit components after cali-bration shall not affect accuracy of the trans-mitted data and that response of the tempera-ture element shall not be substantially affected by incident radiation.

Our invention further resides, in features of construction, combination and arrangement hereinafter described or disclosed.

A later form of our invention having additional features not herein shown is disclosed in co-pending application Serial No. 613,151, filed August 28, 1945, by Robert P. Bennett.

Referring to the drawings:

Figure 1 is a general vertical sectional view showing the location of the various major com-ponents in one embodiment of our invention. The view shows the appearance of the device while being lowered by parachute and before the legs or antenna have assumed their erected positions.

2
Figure 2 shows the weather station after erec-tion of the legs and antenna.

Figure 3 is an enlarged sectional view taken on section 3—3 of Figure 1 showing the para-chute release pin and the tension spring used to eject the parachute cable.

Figure 4 is a sectional view taken on section 4—4 of Figure 1 showing the parachute release pin and the explosive charge used to release the 10 parachute.

Figure 5 is an enlarged sectional view taken on section 5—5 of Figure 1 showing the means used to release the legs.

Figure 6 is a vertical sectional view of the 15 telescoping antenna and the associated reservoir.

Figure 7 is a detailed sectional view of one of the joints of the antenna shown in Figure 6.

Figure 8 shows in partial section the housing used for the temperature-sensitive resistance 20 element.

Figure 9 shows the pressure-sensitive device and the associated variable resistor.

Figure 10 shows the circuit used to provide 25 sequential operation of the erecting and trans-mitting functions.

Figure 11 is a simplified schematic diagram of the relaxation oscillator and crystal oscillator.

Referring now to Figure 1 of the drawings we 30 have shown a general sectional view of one em-bodiment of the device. It will be seen that the housing is shaped in the manner of a bomb. This structure is indicated generally by the nu-meral 20 and consists of a nose portion 22, a longitudinal supporting member 24, a transverse shelf or spider 26, and longitudinal shelf-sup-35 porting straps 28. A yoke 30 connecting the spider 26 and the nose portion 22 is provided to enable attachment to the bomb rack of an air-craft. Two additional transverse shelves 32 and 34 are used for the mounting of the vari-40 ous components to be described. The compo-nents are mounted so as to cause the center of gravity to be as close to the bottom as possible to increase the tendency of the device to remain upright.

To make the device self-erecting without the use of legs, the center of gravity may be lowered by the addition of additional weight 36 placed as low as possible and, in addition, the diameter of the nose may be considerably in-45 creased.

Provision is made at the end opposite the center of gravity for the attachment of a para-chute (not shown) having shroud lines 38. The shroud lines are connected to a rigid rod 40 50 extending down into the center of the structure

for attachment. The rod 40 extends sufficiently beyond the top of the device so that the shroud lines 38 clear any components extending above the upper shelf 32. A lead line 42 is connected from a shroud to the dowel pin 44 of an arming switch 46, the functions of which will be described below. During transportation the parachute is packed in the space indicated generally by the numeral 48.

To erect the device, legs 50 are provided which are hinged to the spider 26 by hinges 52; springs 54 are provided to bias the legs downwardly toward the nose 22. The leg releasing mechanism indicated generally by the numeral 56 controls release wires 58.

The pressure-responsive device 60, the temperature-responsive device 62 and the humidity-responsive device 64 initiate the signals to be transmitted. These weather responsive devices are switched into the radio circuit by clock 66. The radic and electrical portion of the device is illustrated in block form in Figure 1 and consists of the relaxation oscillator 68, the transmitter 70, and the power supply consisting of dry batteries, 72. If desired the power supply may be mounted within the nose portion. The antenna for the radio transmitter consists of a telescoping vertical antenna 74 which is elevated by gases generated in the explosive reservoir 76. Switch 78 consists of concentric annular contacts 80 designed to be shorted by the shorting strips 82. This switch controls parachute release device 84.

Figure 2 shows the weather station in the erected position with the legs 50 drawn downwardly by the action of springs 54 and with the antenna 74 extended. The protection afforded the weather responsive units by the legs has been removed by erection and the elements are fully responsive to ambient conditions.

Figure 3 shows in detail the device used for quickly releasing the parachute. A spring 86 is connected between the parachute rod 40 causing rapid ejection of the rod 40 upon removal of the pin 88. This spring serves both to eject the rod without delay and to apply constant lateral pressure on pin 88 to prevent accidental displacement of the pin. It will be obvious to one skilled in the art that instead of using the rigid rod extension 46 of the parachute line, much the same effect may be achieved by using a line flexible all the way to the point of attachment to the release mechanism and by simultaneously increasing the upward extent of tube 24 sufficiently to clear all obstructions projecting from the upper shelf 32. In lieu of extending tube 24 a lead through device or eyelet spaced from shelf 32 could be used for this purpose.

The specific explosive release device used is shown in Figure 4. The explosive is housed in chamber 90 and is fired by fusible link 92 to which power is supplied by means of the electrical lead 94. A similar device is shown in Figure 5 for releasing the legs 50 held in position by wires 58. The explosive contained in the chamber 96 is fired by the fusible element 98 supplied by electrical lead 100.

Figure 6 shows the telescoping antenna 74 and the reservoir 76. An explosive device 102 is used to provide gas pressure in the reservoir. This pressure feeds into the lower chamber 104 within the antenna barrel 75 at a reduced rate due to the relatively restricted path presented by the connecting tube 106. The antenna consists of a number of telescoping sections designated as 108, 110, and 112 fitting within the barrel 75.

Gaskets 113 are provided to prevent the passage of gas between the respective walls of the tubes or sections. Split annular friction rings 114 are mounted in the annular retaining caps 116 at the top of each section. An enlarged portion 118 is provided at the base of each section to engage the split rings 114 as later described. Apertures 120 are provided to lead the expanding gas from each section to the section immediately above.

The function of the split rings 114 is shown to better advantage in Figure 7. Full extension of any antenna section relative to an adjacent section causes engagement of the enlarged portion 118 and the split ring 114. This frictional engagement has two useful effects. The first is to absorb the kinetic energy of the moving antenna section, the second is to provide a frictional engagement which prevents the telescoping of the two sections with respect to one another except by the application of intentional effort. In operation pressure created within the reservoir 76 is applied to the lower chamber 104 of the antenna barrel 75. Due to the obstruction of the rapid flow of gases caused by interconnecting tube 106, the antenna barrel 75 and its sections 108 and 110 may be constructed of relatively light gauge material. Pressure in the chamber 104 is immediately effective to raise the first section 108 of the antenna. Admission of gas pressure to the chamber 112 immediately above is hindered by the relatively constricted orifice 120. Gas pressure appears in the second chamber 112 only after the high initial gas pressure has been effective to overcome any static friction existing between the first movable section 108 and the antenna barrel 75.

Figure 8 shows a detailed view in partial cross section of the housing for the temperature-responsive element. The housing consists of spaced overlapping cup members 124 surmounted by a cover 126. The outer surface of each cup member is provided with a light-reflecting surface. The inner surface may be darkened to prevent the reflection of light received from the outer surface of the cup immediately below to the temperature-sensitive element 134. Each cup-shaped member is provided with a radially extending flange 128. Longitudinal pins 130 engage the flanges and spacing is provided by the washer-like spacers 132. The resistance element 134 sensitive to changes in temperature is resiliently suspended within the housing by any suitable means of low heat conductivity.

Figure 9 is a detailed view of the pressure-responsive device 60. It comprises a frame 136 to which a bellows 138 is attached by means of a bracket 140. The free end of this bellows terminates in an axially movable rod 142 pivoted to a resistance-controlling lever 144. The collar 146 is provided on the movable rod 142 to interfere with bracket 148 and thus prevent excessive expansion of the bellows when the device is carried at high altitudes. Lever 144 is effective to vary the wire wound resistance element 150. A buzzer 152 is mounted to cause vibration just prior to the insertion of resistor 150 into the relaxation oscillator circuit. Such vibration overcomes both the friction in the bearings, which may be increased by deformation of the members upon impact of the weather station upon the ground. The tensile spring 154 takes up the slack in the mechanical system. The hygrometer or humidity-sensitive device 64 also includes a buzzer to overcome the effect of friction. The hygrometer may be of the well known hair type and may

move a resistance-controlling arm in the same manner as the pressure responsive device.

Figure 10 shows the switching system used to provide sequential operation of the explosive devices and sequential transmission of weather data. An electric clock 154 provided with two sets of contacts performs the switching operation. The hour hand 156 makes contact with contacts 157 once every three hours in the embodiment described while the minute hand 158 makes contact once every minute after the first contact of the series is engaged. Current is supplied to the winding 159 of the clock from battery 160, relay current is supplied by battery 162, and filament and fuse current is supplied by battery 164. All three batteries are disconnected from their respective circuits by the action of the triple pole single throw arming switch 46, which is energized as the weather station is dropped from the aircraft.

Assuming that the hour hand 156 has made contact, negative potential will appear on the minute hand 158. As the minute hand touches the first contact 166, relay 168 is energized, picking up contacts 170. Closing of these contacts supplies potential from battery 164 to the fusible link 92 of the parachute releasing device 84. The making of the first contact is a safety precaution; the fuse 92 will normally have been operated by closing of the nose switch 78 upon contact with the ground. The second contact 172 is effective to energize the leg release relay 174. This results in the closing of contacts 176 and the firing of the fusible element 98 in the leg releasing device. Contact of the minute hand 158 with the third contact 178 causes the picking up of the relay 180, the closing of contacts 182 and the firing of the antenna-erecting explosive device 102. Contacts controlling other erecting functions could be included if necessary at this point.

The subsequent making of the contact 184 causes relay 186 to be energized, which in turn closes contacts 188, putting the reference resistance 190 into the grid circuit of the relaxation oscillator as will be described. Contact 192 causes energization of relay 194, the closing of contacts 196 and the insertion of the pressure-responsive resistor 198 into the oscillator grid circuit. In like manner contacts 200, 208, and 216 through the medium of relays 202, 210, and 218 cause the respective insertion of the temperature-responsive resistor 206, the humidity-responsive resistor 214, and the identification resistor 222, into these circuits. The final making of contact 224 causes reinsertion of the reference resistor 190.

It will be noted that the firing of the leg releasing fuse 98 is accompanied by operation of the buzzer or vibrator 152 associated with the pressure-responsive device 60. In like manner, a buzzer 226 placed in parallel with the antenna erecting fuse 102 is effective to vibrate the humidity responsive device 64. It will also be noted that the buzzers 152 and 226 operate for an extended period, approximately 45 seconds, prior to the insertion of the associated resistance into the relaxation oscillator grid circuit. The vibration counteracts friction and enables the weather-responsive device to assume a true equilibrium position.

The filaments of the transmitter tubes are turned on by relay 228 which is in series with the resistance-switching relays 186, 194, 202, 210, and 218. Thus, filament power is applied only during

periods of actual transmission, as will be seen below, thereby saving the battery 164. By putting the hands of the clock 156 and 158 in series as shown, the sequence described above will only take place once every three hours.

Figure 11 shows the relaxation oscillator circuit designated generally as 230, the crystal oscillator circuit 232 and the radio frequency (R. F.) amplifier 234. The relaxation oscillator 10 comprises a vacuum tube 236 of any well known type having a high value of trans-conductance and a transformer 238, consisting of windings 240 and 242. The time constant of the oscillator is determined by the capacitor 244 and the resistor 15 which may be inserted into the circuit. Such resistor, indicated generally by numeral 246, may be any one of the resistors 190, 198, 206, 214, or 222, discussed in connection with Figure 10. The use of small additional capacitors 248 and 250 in a relaxation oscillator circuit is well known. A relay 252 is provided in the plate circuit of the relaxation oscillator tube. The contacts 254 of this relay short out the grid bias applied through resistor 255 associated with the 25 crystal oscillator tube 256 to start oscillation of the crystal oscillator circuit. The interrupted oscillations are amplified and broadcast by the radio frequency amplifier 234.

The relaxation oscillator operates as follows: 30 Assuming a sudden application of plate voltage, increasing plate current will result in a positive potential being applied to the grid of vacuum tube 236. This positive potential will result in the flow of grid current which charges capacitor 244. 35 When the plate current becomes constant at a saturated value, no positive voltage is induced at the grid terminal of the secondary 242 of the transformer. The plate current will therefore start to decrease, such decrease inducing a negative potential at the grid of the tube cutting off the plate current. The plate current is kept in the cut-off condition by the negative charge which has collected during the previous half cycle on the capacitor 244. This charge is dissipated through resistor 246 and, after the time 40 interval required for such dissipation, the grid will lose its negative potential and the entire cycle will be repeated. The capacitor 244 in the time constant circuit is large, on the order of 8 microfarads, while the resistor 246 is on the order of 10,000 ohms. This results in a desirable slow pulse rate on the order of $\frac{1}{2}$ to $3\frac{1}{2}$ pulses per second.

Before use the relaxation oscillator is calibrated with the weather-responsive elements so that each condition of pressure, temperature, and humidity corresponds to a certain pulse rate. The altered characteristics of other components in the circuit, caused for example by aging or damage, may cause a pulse rate somewhat slower or faster than the calibrated value for a given value of grid resistor. This error may be eliminated by the use of the reference resistor 190. The pulse rate resulting from the insertion of the reference resistor 190 in the grid circuit is noted at the time of initial calibration. Later in actual use the reference resistor 190 is switched into the grid circuit by the clock 154 prior to the resistors associated with the weather-sensitive devices. If it is noted that the pulse rate for the reference resistor is, say, 5 percent too fast, the pulse rate noted for each of the other resistors will be corrected by being reduced proportionately before the pulse rate is interpreted as a weather condition.

The intended use of the device is as follows: The weather station with its legs 50, held in the position shown in Figure 1 and with the parachute packed in space 48 provided, is loaded on the bomb rack of an aircraft. A static line is rigged from the aircraft to the parachute to pull the parachute free immediately after the device is released. A lead line 42 is attached to one of the shrouds 38 of the parachute and to the dowel pin 44 which holds the arming switch 46 in an open position thus preventing the batteries from energizing any of the circuits. The clock 154 may be present to energize the associated leg or antenna-erecting contacts after a dormancy period of up to approximately three hours after the arming switch 46 has been operated.

When a suitable location for the station has been determined, the station is dropped. The static line causes the parachute to open lowering the station at a rate of approximately 8 feet per second. At the same time opening of the parachute causes arming switch 46 to apply power to start the clock 154 and to connect batteries 160, 162, and 164 into the circuit. Upon impact with the ground, the nose switch 78 will close, firing the parachute releasing device 84 and preventing the station from being pulled along the ground. The device will lie inert for the pre-set dormancy period until the first contact 166 is made by the clock 154. A long dormancy period may be of use where it is intended that the device lie unerected until darkness has fallen in order to escape enemy detection. Contact 166 is effective to release the parachute if nose switch 78 has failed to do so.

Contact of the minute hand with the second terminal 172 of the clock will cause operation of the leg release device 56. Assuming that the device has landed on its side, the release of the legs 50 will, due to the urging of springs 54, cause the device to become upright as shown in Figure 2. This may be readily accomplished by springs 54 of reasonable size if the device has a low center of gravity.

As the minute hand of the clock touches the third contact 178, the antenna erecting explosive device 182 is fired causing erection of the antenna as discussed above.

The contact of the minute hand with contacts 192, 200, 208, 216, and 224 results in the consecutive insertion of the reference resistor 198, the pressure-responsive resistor 198, the temperature-responsive resistor 206, the humidity-responsive resistor 214, and the identification resistor 222. While it will be obvious to one skilled in the art that the spacing of the clock contacts and the contact width may be adjusted over wide limits, the following program has been found to be satisfactory:

Signal	Time (approximate)
Reference.....	45 Seconds.
Silence.....	15 Seconds.
Pressure.....	45 Seconds.
Silence.....	15 Seconds.
Temperature.....	45 Seconds.
Silence.....	15 Seconds.
Relative Humidity.....	45 Seconds.
Silence.....	15 Seconds.
Identification.....	45 Seconds.
Silence.....	15 Seconds.
Reference.....	45 Seconds.
Silence.....	2 Hours, 54 Minutes.

While the identification signal which notifies the operator to which station he is listening has a separate resistor in the embodiment described, the identification function could also be per-

formed by using a distinctly different pulse rate for the reference signal of each weather station used.

At the receiving station the transmitted pulses are counted over a measured time interval and the pulses per unit time readily computed. Calibration charts enable the pulse rates to be interpreted as weather conditions. Assuming that dry batteries are used, reasonable battery power is sufficient to cause the station to transmit the above program of signals every 3 hours for a period in excess of 15 days.

When the station is to be used only as a beacon, the radio transmitter and its control mechanisms may be simplified merely to transmit a signal which may be used to guide for example other craft equipped with radio-direction-finding apparatus.

While we have shown and described particular embodiments of our invention, it will occur to those skilled in the art that various changes and modifications can be made without departing from our invention, and we, therefore, aim in the appended claims to cover all such changes and modifications that follow in the true spirit and scope of our invention.

The invention described herein may be manufactured and used by or for the Government of the United States of America for governmental purposes without the payment of any royalties thereon or therefor.

What we claim is:

1. An automatic radio station adapted to be lowered by parachute comprising, an elongated 35 housing having its center of gravity near the bottom end, a parachute suspension line having its point of exit at the top end of said housing remote from said center of gravity, an explosive parachute release device to release said suspension line, a nose portion on said housing at said bottom end, a set of electrical contacts mounted on said nose portion to operate said release device upon contact with the earth, a quick acting fusible element in said explosive release device operated by said electrical contacts whereby positive release is obtained with only momentary contact of said electrical contacts.

2. An automatic radio station adapted to be lowered by parachute comprising an elongated 50 housing having its center of gravity near its bottom end, a plurality of legs hingedly attached to said housing at spaced points about said housing at a level above said center of gravity, said hinge attachment enabling each of said legs to swing in 55 a plane which includes the axis of said housing, biasing means to urge said legs toward said bottom end of said housing, retaining means to hold said legs along the side of said housing against the action of said biasing means, and releasing means operable after contact with the earth to erect said housing into a leg-supported position.

3. An automatic radio station adapted to be lowered by parachute comprising an elongated 60 housing including a frame, a parachute suspension line, a parachute suspension line lead through device mounted at the end of said housing at a point spaced sufficiently far from the end of said housing so as to minimize the possibility of fouling of said suspension line with 65 components projecting from the end of said housing, a parachute suspension line engaging member engaging said suspension line and mounted within said housing at a point of great mechanical strength of said frame whereby the likelihood of 70 damage to said housing caused by the jerk of said

parachute suspension line upon opening of said parachute is reduced.

4. The subject matter as claimed in claim 3 including a spring having one end engaging said parachute suspension line within said housing and the other end engaging said lead through device whereby said suspension line is quickly and forcibly ejected from said lead through device upon release of said line from said line-engaging member.

5. An automatic radio station adapted to be lowered by parachute comprising an elongated housing including a frame, a parachute suspension line, a parachute suspension rod fastened at the end of said suspension line to support said housing, said rod projecting outwardly from said housing to a point sufficiently far from said housing as to minimize possible fouling of said suspension line with components projecting from the end of said housing, said parachute suspension rod projecting into said housing to a point of great mechanical strength of said frame, a parachute release device engaging said rod and mounted at said point of great mechanical strength, and a spring having one end engaging said parachute suspension rod within said housing and the other end engaging said housing at the point of entry of said rod, whereby said suspension rod is quickly and forcibly ejected from said housing upon release of said rod by said parachute release device.

6. An automatic radio station adapted to be lowered by parachute comprising a housing, a nose portion on one end of said housing, a parachute supporting line entering said housing at a point remote from said nose portion, an explosive parachute release device engaging said parachute supporting line, a set of electrical contacts mounted on said nose portion to energize said explosive release device upon impact with the earth, an arming switch mounted on said housing having electrical contacts in series with said nose electrical contacts, an arming switch operator engaging said parachute supporting line effective to cause said arming switch to close upon opening of said parachute, whereby operation of said explosive release device is not possible until after said station is parachute-supported.

7. An automatic radio station adapted to be lowered by parachute comprising a housing, a parachute supporting line engaging said housing, an explosive release device to free said parachute

supporting line from said housing, an explosive erecting device to erect said station for use, an arming switch having electrical contacts in series with said explosive release device and said explosive erecting device, an arming switch operator engaging said parachute supporting line and effective to cause said arming switch to close upon the opening of said parachute, whereby operation of any explosive devices is not possible until after said station is parachute-supported.

8. An automatic self-erecting radio station adapted to be dropped by parachute from aircraft comprising, an elongated housing having its center of gravity near its bottom end, a plurality of legs hingedly attached to said housing at spaced points about said housing at a level above said center of gravity, spring biasing means urging said legs to be swung outwardly from said housing toward said bottom end of said housing for the purpose of self-erection and support, retaining means effective until said station is dropped to hold said legs adjacent the sides of said housing against the action of said biasing means, said legs being of such length and so positioned as to project beyond the top end of said housing forming a receptacle for the temporary storage of a self-contained parachute.
